Application October 15, 1948, Serial No. 54,770

6 Claims. (Cl. 315—278)

1

This invention relates to an electrical apparatus and particularly to a ballast for fluorescent lamps. The invention in particular relates to a ballast which is corrected for power factor and is for use with one fluorescent lamp on an alternating current circuit whose potential is normally over one-half of the desired running potential.

The invention makes it possible to provide a simple and economical ballast which may be designed to operate in a satisfactory manner for both starting and running conditions. The general background problem for this invention will most easily be understood after the specific invention has been described.

The invention will be described in connection with the drawing wherein Figure 1 is a circuit diagram illustrating the invention and Figure 2 is a plan view partly in section of a ballast embodying this invention.

Referring now to the drawing, a series of windings 10, 11, 12 and 13 are disposed upon leg 15 of laminated core 16. Leg 15 and opposing leg 17 are joined by short connecting legs 18 and 19 providing window 20. The relatively close spacing between long legs 15 and 17 of the core provides a substantial leakage path for magnetic flux. Other cores providing desired leakage may be used.

As shown in Figure 2, winding 10 is disposed over part of leg 15 and winding 11 is disposed over winding 10. Disposed over the remainder of leg 15 is winding 12. Over winding 12 is winding 13. Windings 12 and 13 are closely coupled. Windings 10 and 11 are also closely coupled. Windings 10 and 11 are loosely coupled to windings 12 and 13, although the coupling to 13 is unimportant.

Windings 10 and 11 may be one continuous winding with an intermediate tap. The same is true of windings 12 and 13. It is understood that the core is made up of conventional laminations to permit ready positioning of the windings. The junction of windings 10 and 11 is connected by lead 22 to condenser 23 whose other terminal is connected by lead 24 to the bottom end of winding 13. The junction of windings 11 and 12 is connected to wire 26 while the junction of windings 12 and 13 is connected to wire 27. Wires 26 and 27 are for connection to a conventional alternating current supply circuit.

The free end of winding 10 is connected by lead 30 to filament 31 and thence by lead 32 to starting switch 33. The circuit from starting switch 33 continues along lead 34 to filament

2

35. Filaments 31 and 35 are part of fluorescent lamp 36 of a type available on the market. The circuit from filament 35 continues by way of lead 37 to the junction of windings 12 and 13.

5 If winding 11 is omitted, with wires 22 and 26 connected together on the ballast, then the structure assumes a conventional form common in the prior art. It will be convenient to assume that winding 11 is omitted and discuss the shortcomings of the prior art.

When a lamp has broken down at the beginning of a cycle, the discharge has the nature of a glow or arc and has a negative resistance. For this reason, it is necessary that ballast means 10 be provided to impart stability to the lamp circuit as a whole. After the discharge has been initiated, the lamp current should be limited to a predetermined figure to conform to the rated wattage of the lamp. As a rule, the limits for 15 departure from such predetermined conditions are not very great, if maximum benefit from the lamp is to be assured.

When such a lamp is started, it is customary to dispose the filaments in series by means of 20 a starting switch. The wattage for and duration of preheating the lamp are interrelated and predetermined to conform to the specifications of both the lamp maker and starting switch maker. As a rule, automatic starting switches 25 are designed to maintain the filaments heated for a predetermined time. Hence the starting current for a lamp must in general conform to predetermined limits. Assuming the usual 60 cycle 110 volt supply, fluorescent lamps such as the 30 or 40 watt variety, require a specified 200 volts for running.

Referring now to the circuit diagram of Figure 1, minus winding 11, the potential from line wires 26 and 27 is stepped up by autotransformer action in windings 10 and 12 to a potential suitable for lamp 36 under normal running conditions. Winding 13 and condenser 23 operate in the usual manner for power factor correction. Under such conditions, the lamp presents a substantial resistance load and together with the reactance of the ballast limits the load current to a predetermined normal value.

Now assume that the lamp has started with switch 33 closed. The lamp load is practically zero and consists of the pure resistance of the two filaments in series. In comparison to the rest of the circuit, this is negligible. Hence at starting, the load may be considered as a short circuit. Still assuming that winding 11 is omitted, it will be apparent that the short circuit

effectively disposes winding 10 across winding 12. If windings 10 and 12 are designed to provide the normal potential for running conditions, saturation will occur in the magnetic circuit of winding 10 unless the step up ratio is 2 to 1 or more. It is readily seen that to produce this ratio when not required otherwise, will result in a transformer design of higher volt ampere capacity also requiring greater power factor correction. This condition could also be overcome by a specially designed core structure at the expense of an inefficient use of core material and space.

It is possible to maintain winding 10 at the value for running conditions and operate the core at a low flux density. Then at starting, the flux density will be increased to a normal value. This however represents a wasteful use of iron, making the ballast expensive and bulky.

The running conditions will not be adversely affected if starting conditions are favored, but rather the design must be based on considerations of the worst or most extreme conditions. Generally, this would be the starting conditions. The result is that the design for running conditions would be too conservative or inefficient so far as the cost of constructing the ballast is concerned.

This invention varies the circuit so that a circuit parameter is provided which is not equally effective for both starting and running. Thus the number of turns of winding 11, within limits, may be varied and when so varied will have a substantial effect upon the starting current but have negligible effect upon the running power consumption of the lamp. It has been found that when winding 11 has more turns than the starting current is decreased. As a rule, winding 11 may have from about 5% up to about 20% of the turns of winding 10. Preferably the ratio is from about 7½% to about 15%.

The arrangement of the windings, as regards coupling, is shown in Figure 2. The design of a ballast in general will follow along conventional lines. Thus the turns and turn ratio of windings 10 and 12 will generally follow conventional lines. Similarly winding 13 and condenser 23 will follow conventional values. It is understood that the value of condenser 23 is one of the parameters in the design of a ballast, this being well understood in the art.

The turns making up winding 11 will be found to have a highly beneficial governing effect upon the intensity of the starting current. The value of winding 11 for most efficient results will be dependent upon the precise values of the remainder of the windings, value of condenser and dimensions of the core.

In large measure, the exact design is a function of desired characteristics of the ballast. The ballast casing is usually of iron and sufficiently close to the windings and core so that it has substantial effect upon the performance of the ballast. Thus the casing will also have to be considered.

Preferably the circuit containing the condenser is designed so that the current therein under running conditions is about equal to the normal running current through the lamp. The current in the condenser circuit does not change greatly from starting to running.

Winding 11 has the currents therein generally more than 90° out of phase with currents in winding 10. Hence it is possible to use finer wire for winding 11 than for winding 10. However, it is

generally simpler to wind 10 and 11 as one continuous coil and take a tap off for wire 22. In any event the internal losses contributed by the addition of winding 11 will be negligible.

5 The new ballast, when operating under starting conditions, will be found to limit the starting current to a desired value substantially below what would ordinarily be the case if winding 11 were omitted. At the same time the core may 10 be designed for efficient and effective operation under running conditions and starting conditions. What is claimed is:

1. A ballast for fluorescent lamps of the type having two separate filamentary cathodes with a starter switch connected between one terminal of one cathode and one terminal of the other cathode, said lamp having both filamentary cathodes connected in series upon starting and drawing a heavy current to energize both cathodes, said ballast comprising a ferromagnetic laminated core having substantial leakage flux, four windings connected in series and disposed on said core, the first and second windings being magnetically additive and closely coupled, the third and fourth windings also being magnetically additive and closely coupled, the first two windings being loosely coupled to the last two windings, said first winding having one free terminal forming a ballast terminal for connection to the other terminal of one cathode, the terminals of the third winding forming ballast terminals for connection to an alternating current power line, the common terminal of the third and fourth windings forming a ballast terminal for connection to the other terminal of the other cathode, a condenser connected across the second, third and fourth windings, said second winding having less than 20% of the turns of the first winding, the first and third windings being proportioned to provide rated running current to the lamp with the running potential across the first winding being less than the normal potential across the third winding, said condenser and fourth winding being proportioned 30 to provide power factor correction during running, said second winding having negligible effect under running conditions but effective under starting conditions to reduce current through the first winding whereby the core may operate under both starting and running conditions at normal flux densities, without substantial saturation at starting or without magnetically inefficient low flux density under running conditions.

55 2. The ballast, according to claim 1, wherein said second winding has between about 5% and 20% of the turns of the first winding.

3. The ballast, according to claim 1, wherein the second winding has between about 7½% and about 15% of the turns of the first winding.

4. The ballast, according to claim 1, wherein the ferromagnetic core has a generally rectangular outline with a long narrow window and wherein the four windings are divided into two groups in side by side relation on the long leg of the core, each group consisting of an inner winding and an outer winding, the two windings in a group being closely coupled.

60 5. The ballast, according to claim 1, wherein the ferromagnetic core has a long, narrow, generally rectangular window with the four windings disposed on a long leg, the first and second windings forming one group and the third and fourth windings forming another group, said two

groups of windings being disposed in side by side relation, each group having the windings disposed to form inner and outer windings, the second winding having between about 5% and about 20% of the turns of the first winding.

6. The ballast, according to claim 1, wherein the ferromagnetic core is shaped to provide a long, narrow, generally rectangular window with all windings disposed upon a long leg, said first and second windings forming one group and said third and fourth windings forming a second group, said two groups of windings being disposed in side by side relation, each group having the windings arranged to provide inner and outer windings, the second winding having be-

tween about 7½% and 15% of the turns of the first winding.
